SAFETY DEVICE FOR CLOTHESLINES

Rudolph K. Brown, Jersey City, N. J.

Application March 10, 1943, Serial No. 478,614

1 Claim. (Cl. 211—119.07)

The present invention relates to certain new and useful improvements in clothes-lines and it relates more particularly to a safety device for a pulley-type clothes-line.

An object of the present invention is to provide a simple, inexpensive and dependable safety device adapted for use on pulley-type clothes-lines which will minimize the danger of accidents and which, at the same time, will greatly reduce the labor and strain ordinarily present in hanging clothes. Another object of the present invention is to provide a safety device for a pulley-type clothes-line which is adapted for connection to a window frame or the like and which can be adjusted to bring one end of the clothes-line into the room during hanging or removing of clothes and which can be locked outside the window at other times.

Other objects and advantages of the present invention are present in the following detailed description, appended claim and accompanying drawing.

For purposes of illustration there is described hereinbelow one form of the present invention which has been found in practise to give satisfactory results. However, it is to be understood that the present invention is not limited to the instrumentalities and arrangements herein shown and described.

Referring to the accompanying drawing in which like reference characters indicate like parts throughout:

Figure 1 represents a perspective view of one embodiment of the present invention as it appears while clothes are being hung or removed.

Figure 2 represents a plan view and partial section of the embodiment of Figure 1; the position of the several parts after the device has been swung out but not yet locked being shown in dotted lines.

Figure 3 represents a view partly in elevation and partly in vertical cross-section of the embodiment of Figure 1 as it appears after it has been locked in its outside position.

Figure 4 represents a perspective view of the parts of the hinge assembly in dis-assembled position.

In the embodiment shown in Figures 1 to 4 of the drawing, one leaf 10 of a hinge 11 is more or less permanently and immovably attached to the outer face of a window frame 12 by the screws 13 at a point slightly below the center of the window. The other leaf 14 of said hinge 11 is affixed, by means of the screws 15, to the larger 55

end of a tapered arm 16 which is preferably of wood or other inexpensive and easily formed material; the leaf 14 and its associated arm 16 being free to swing around the hinge-pin 17 which will be described in detail hereinbelow.

The smaller end of the arm 16 carries a hook 18 disposed generally on one side thereof. One pulley 19 of a clothes-line 20 is adapted removably to be mounted upon the hook 18; the other pulley 21 of said line 20 being mounted upon a pole 22 or the like in conventional manner.

The hinge-pin 17 has a hook-like portion 23 formed at one end thereof; the straight portion 24 of said hinge-pin 17 being sufficiently long to extend somewhat above the upper edge of the leaves 10 and 14 when inserted through the apertured meshing tongues thereof. A small sheave-wheel 25 is rotatably mounted upon the upper protruding portion of said hinge-pin 17. A curved guard 26 is mounted at one end upon the leaf 10 in any conventional manner, as for example, by being passed through a small hole 27 formed in said leaf and being thereafter peened against the leaf to lock it in place. A loop 28 is formed at the other end of said guard 26. The loop 28 is in line with the hinge-pin 17 so that the upper end of said hinge-pin, after passing through said sheave-wheel, passes through said loop. A transversely extending hole 29 is formed at the uppermost end of said hinge-pin 17 above said loop 28 and is adapted to receive a cotter-pin 30 which locks the hinge-pin assembly in place.

35 A hook 31 is swivelably mounted on the arm 16 upon the side opposite the hook 18. The hook 31 is adapted to co-act with an eye 32 mounted on the inner face of the window frame 12 to lock the arm 16 in its inwardly extending position.

The upper run of the clothes-line 20 runs from the outside pulley 21 inside the guard 26 and over the sheave-wheel 25 and from there to the pulley 19. The lower run of the clothes-line 20 either 45 extends directly from the pulley 19 to the pulley 21 as shown in Fig. 1 or can be positioned behind the hook-like portion 23 of the hinge-pin 17 as shown in Fig. 3.

When it is desired to hang clothes, the lower window is raised, the arm 16 is swung inside the room, the hook 31 is connected to the eye 32 to lock the arm in its inwardly extending position and the lower run of the clothes-line 20 is disconnected from the hook-like portion 23. As can be seen from Fig. 1, it is then possible

to hang (or to remove) clothes on the line without having to lean out of the window as is necessary with conventional clothes-lines. In this way, not only is the danger of falling out of the window virtually eliminated, but also the time and effort involved in hanging (or removing) clothes is greatly reduced since it is no longer necessary to bend over and to hold the clothes in an awkward extended position during the operation.

After the hanging operation has been completed and the clothes run out on the line to dry, the lower run of the line 20 is again placed behind the hook-like portion 23, and the arm 16 unhooked and swung outward to the position shown in dotted lines in Fig. 2; the clothes-line 20 being maintained taut during the swinging operation by the sheave-wheel 25 and the hook-like portion 23. Since the arm 16 has a tendency to swing in a wind, I prefer to lock it in the position shown in Fig. 3, by inserting the pulley 19 (which has a diameter somewhat greater than the distance between the hook-like portion 23 and the sheave-wheel 25) between the upper and lower runs of the line 20 and also by hooking the hook 31 behind the upper run of the line.

The window can then be closed and the clothes allowed to dry whereupon the window is opened, the arm 16 is disconnected and swung in and locked to the eye 32, the line 20 is unhooked from the portion 23 and the clothes pulled in and removed from the line without danger and with a minimum of time and effort.

The sheave-wheel 25 permits the line to run freely and easily and prevents fraying and wear thereof especially when the pole 22 is not directly in line with the window so that the clothes-line 20 makes a relatively sharp angle in passing over the sheave.

The construction of my device also permits quick and easy dis-assembly thereof so that it is impossible to replace parts readily and inexpensively.

The safety device of my present invention can be constructed at a low cost with a minimum of "special" or difficult to make parts. Thus the hinge-leaves 16 and 14 may be the leaves of an ordinary conventional door-hinge. The hinge-pin 17 may be readily formed from an ordinary metal rod by bending up one end and drilling or otherwise forming a hole therethrough at the other end. The hooks 18 and 31, the eye 32 and the sheave-wheel 25 are all standard parts which are readily and inexpensively obtainable

on the market. The arm 16 can be formed and assembled with a minimum of time and expense.

The present invention may be embodied in forms other than that shown and described herein and it is therefore to be understood that the embodiment shown and described herein is by way of illustration and not restriction, reference being made to the appended claim rather than the foregoing description to indicate the scope

of the present invention.

Having thus described my invention, what I claim as new and desire to protect by Letters Patent is:

A safety-device, adapted to support one end of a clothes-line or the like and to be swung into position inside a room for hanging and removing clothes and adapted also to be reversely swung into position outside the room without slackening the clothes-line, comprising a hinge-leaf 15 adapted to be immovably affixed to a window frame or the like, a second hinge-leaf 16 swingably attached to the fixed leaf by a hinge-pin having a bent hook-like portion formed at its lower end, the lower run of the clothes-line being adapted 20 to be hooked over said hook-like portion when the device is to be swung outwardly and being adapted to be unhooked from said hook-like portion when the device is to be swung inwardly, said hinge-pin passing through and extending 25 upwardly beyond meshing apertured tongues on said leaves, a sheave 25 rotatably mounted on the upwardly extending portion of said hinge-pin and over which the upper run of said clothes-line is adapted to pass, a guard fitting over said 30 hinge-pin above said sheave, a retaining pin extending through a transverse opening formed in the uppermost end of said hinge-pin above said guard, a relatively thin elongated rigid arm attached at one end to said movable hinge-leaf and 35 adapted to swing therewith about said hinge-pin, a hook connected to the free end of said arm adjacent one side thereof and adapted detachably to receive a pulley carrying said clothes-line, and an elongated hook swivelably attached to the 40 other side of said arm intermediate the ends thereof, said elongated hook being adapted to engage with an eye mounted on the inside of the window to lock said arm in its inwardly extending position and also being adapted to engage 45 with the clothes-line to lock said arm in its outwardly extending position.

RUDOLPH K. BROWN.
